UNITED STATES PATENT OFFICE

OLIVER M. KNODE, OF WINNETKA, ILLINOIS, ASSIGNOR TO UNITED STATES GYPSUM COMPANY, OF CHICAGO, ILLINOIS, A CORPORATION OF ILLINOIS

PLASTER-WALL-BOARD CONSTRUCTION

Application filed September 25, 1922. Serial No. 590,358.

This invention relates to improvements in building materials and more particularly to plaster wallboard construction.

In the building trade a pulp, composition or 5 plaster panel board that, when nailed to the studding of the interior of a building, may be covered with strips of wood at the joints, painted or papered over without first covering with plaster is called wallboard while 10 other substitutes of lath and plaster that must first be covered with a coat of plaster are called plaster board. In wallboard having a plaster body, the surface covering is of better grade than plaster board and it is extremely 15 important that the longitudinal edges of wallboard are well formed and of uniform thickness so that when the boards are placed edge to edge in forming the wall the surface will be uniform and flat, in other words the surfaces presented will substantially be in the 20 same plane.

This effect is generally produced by covering or binding the longitudinal edges in plaster wallboard to prevent the plaster adjacent 25 the edges becoming broken, crumbling or falling out during handling or transportation which will cause reduced thicknesses at uneven points along the edges and, when applied to the wall, will cause hollows in the wall surfaces. Even with bound or covered edge 30 plaster wallboard it is customary to cover the space between the adjacent edges with a panel strip or fill the crack with a putty like substance called "crack filler" to insure a smooth 35 surface to paint or paper over. It has been found that it is advisable to leave a small space between adjacent edges to allow the crack filler to bond to both boards if a slight hair crack in the filler is to be prevented.

40 It is an object of this invention to provide a plaster wallboard without binding or covering the edge that will maintain consistent thickness of the edge uniformly throughout and at the same time provide a sufficient space 45 between adjacent boards when secured in place upon the wall for the "crack filler" to bond and cover the joint without the formation of cracks between the boards, it being understood that such a wallboard may be applied and plastered over in the manner of a

plaster board in the sense as above defined, may be cut in smaller dimensions of customary plaster board and used as such, made originally in such dimensions, or the seconds or imperfect boards cut down and used as 55 plaster board.

Among the advantages of this invention are that this unbound or raw edge plaster wallboard is more economical to manufacture than one with the covered or bound edge, as this 60 board is completed when it leaves the forming rolls and does not require any further treatment, such as trimming, which not only requires the presence of an operator but causes wastage of paper and plaster, and the improved formation of the edge hereinafter described makes a better joint for crack filler than the rounded or square edged wallboard. 65

While the preferred form of means for constructing this improved plaster wallboard is 70 illustrated on the accompanying sheets of drawing, yet minor detail changes may be made without departing from the scope of this invention.

In the drawings, 75 Figure 1 illustrates in side elevation, a form of apparatus for constructing this improved plaster wallboard, partly in section, showing the board forming end of the machine.

Figure 2 is a top plan view of Figure 1, with 80 parts removed.

Figure 3 is a view in side elevation, partly in sections, of a portion of the machine next adjoining that shown in Figure 1.

Figures 4 and 5 are sectional views taken on 85 the lines 4—4 and 5—5 on Figures 1 and 3 respectively.

Figure 6 is a view corresponding to Figure 4 showing a modification.

Figure 7 is a view in vertical longitudinal section of the part of the modified machine adjacent the section illustrated in Figure 6.

Figures 8 and 9 are views in perspective of 90 forms of plaster wallboard constructed in accordance with this invention, illustrating the transverse edges in sections.

Figure 10 illustrates the manner in which 95 adjacent boards are secured to the studding of a building.

Figure 11 is a view similar to Figure 4 of a modified form of machine.

Wallboard constructed in accordance with this invention comprises a body of plaster, or like material, to which a covering sheet of paper, or fibrous material, is bonded on each side. To construct this improved plaster wallboard a bottom cover sheet 1 is advanced continuously from a roll of paper 2 to the end 10 of a table 3 over which it passes to the forming rolls 4 and 5. As it passes over the table the longitudinal edges 6 each pass over angular shaping members 7 which tilt up the sheet for a short distance adjacent each edge 15 so that as it passes between the forming rolls, a section of the sheet there through will be of dish like conformation, see Figure 4. A pair of holding rolls 8 are preferably provided to exert pressure on the main body of the sheet 20 to hold it flat upon the table as the edges travel up upon the angular shaping members 7 and if it is desired to make the bend in the edges where it tilts up from the body more definite scoring wheels 9 may be employed to 25 impart a reduction in the thickness of the paper at this point and will insure a uniform width between the angular edges 6. As the bottom sheet advances plaster or like material 10 in a plastic state is delivered upon the 30 center of the sheet, preferably by a belt conveyor 11, which may be of the usual construction used in this art.

A top cover sheet 12 is applied over the plastic mass as it passes through the forming 35 rolls by passing it from a paper roll 13 over the upper forming roll 5. The lower forming roll 4 is provided at each end with a tapered conical enlargement 14 corresponding in shape to the angular shaping members 7 on the table. To retain the mass of plastic material upon the bottom cover sheet 1 as it approaches the forming rolls and as it passes there through plates 15, preferably of glass or such material to which the plastic mass will 40 not adhere readily, are arranged on each side of the angular shaping members and extend along both ends of the upper forming roll 5 to a point therebeyond.

The flat table 3 is preferably continued beyond the forming rolls 4 and 5 over which the formed board travels and it is also preferable to provide angular shaping members 16 similar to the members 7 on the other side of the forming rolls and over which the formed 55 beveled edges travel to support the edge in that shape until the plastic body has set more firmly. It is also preferable to extend the plates 15 on each side of these latter members 16 throughout their length which plates extend above them to the top of the formed board. A means for maintaining the edges of both cover sheets in contact with the body of the formed board in the form of belts 17 arranged over each edge is also preferable to insure the bonding of the body to the edges.

From the table 3 the formed board passes onto a conveyor, preferably a continuous belt 18, see Figure 3, which may, if desired, have a shaping member 19 on each side thereof similar to the members 7 on the table for supporting the edges of the board as it travels there-
70 with.

It is also preferable to provide an ironing device through which this conveyor advances the formed board while the plaster body is setting to insure a uniform bond between both cover sheets and the plastic body to produce an even and uniform surface on each side of the board. The ironing device preferably comprises a plurality of rollers 20 arranged under the conveyor belt and over which the belt travels and a corresponding number of rollers 21 mounted in a vertically movable frame 22 arranged over the lower rollers 20 with another belt 23 traveling over rollers mounted at the ends of the frame and passing under the frame rollers 21 and resting upon the upper surface of the board. This frame is weighted and its downward movement is limited by set screws 24 mounted in the frame adapted to rest upon brackets 25 extending from the fixed support of the under rollers 20.
80
85
90
95

After the board has passed through the ironing device it travels forward on the same or another similar conveyor, not shown, for a distance far enough for the plastic body to set sufficiently for the board to be cut in lengths, removed from the conveyor and transported to drying kilns without being deformed.
100

Figures 6 and 7 show a modification of the part of the machine that extends beyond the forming rolls 4 and 5 in which the stationary plates 15 on each side over which the edges of the board pass are terminated at or just beyond the forming rolls, as shown clearly in Figure 7, and vertical belts 26 are mounted on the table extending beyond the forming rolls to take their place. These belts contact with the portion of the edge extending above the shaping members 16 and travel with the board so that the portion of plastic material at the edges of the board do not wipe over a stationary member.
105
110
115

The width of the board is determined by the distance between the plates 15 and the thickness is determined by the distance between the forming rolls 4 and 5. The angle of bevel of the longitudinal edges is determined by the angles of the tapered conical enlargements 14 on the bottom forming roll 4. While it is preferable to score the bottom sheet and tilt up the edges by the shaping members 7 to form a trough to retain the plastic material such construction is not essential for any other means may be employed to retain the plastic material on the sheet, as the bevels at the edges are imparted at the time the top sheet is applied and the board 120
125
130

formed by passing through the forming rolls 4 and 5.

Also while it is preferable to provide shaping members on the table and on the conveyor beyond the forming rolls similar to those in front of the rolls they are not essential if the mix of the plastic material is such that it will have body enough to set sufficiently to maintain the bevel imparted to the edges 10 in passing through the forming rolls.

The object of beveling the longitudinal edges is two fold. The beveled edge permits the ready manufacture of a raw edge board as the beveled part of the cover sheet acts as 15 a retainer for the plastic material of the body during formation and when made prevents the crumbling of the edge. It also presents a V shaped space between the adjacent longitudinal edges when the boards are secured 20 in place, as shown in Figure 10, which space is of sufficient width and depth to be filled with crack filler 26 and make a smooth and continuous surface from one board to another without hair cracks forming in the 25 filler. A still further advantage of this form of edge is that it allows the securing nails 27 to be either driven into the studding 28 through the full thickness of the board or through the beveled portion and in the latter 30 case, the nail heads will be completely covered by the crack filler.

While it is preferable to form the board with the edge of one cover sheet beveled and extended to engage the other flat sheet, as 35 shown in Figure 8, the engagement of the sheets is not essential to this invention as only a slight bevel is necessary to produce the desired results and the top sheet may be beveled and terminated at the edge a distance 40 above the edge of the other flat sheet as shown in Figure 9.

Figure 11 illustrates a modification of the machine by which the board is made with the bottom sheet extending flat throughout 45 and the bevel or tilt given to the top sheet by the top forming roll 5 having a conical enlargement 14' at its ends. In this form the bottom forming roll 4 may be dispensed with and the table extended continuously under the upper roll 5.

What I claim is:

The method of constructing raw edge plaster wallboard having inclined, longitudinal edges, comprising the continuous advancing of a bottom sheet, depositing a mass of plastic material thereon, forming the plastic material evenly upon said sheet, applying the top sheet over said plastic body, forcing one 55 only of the cover sheets at an angle along its longitudinal edges toward but not abutting the other sheet, the edges of the two sheets being separated a substantial distance to expose a portion of said plastic material along 60 the edges of the wallboard, and supporting 65

said exposed plastic material by a belt moving at substantially the same speed as the wallboard in contact with said material until said material has hardened and set.
